UNITED STATES PATENT OFFICE

EVERETT M. SALISBURY, OF PROVIDENCE, RHODE ISLAND

DESIGN FOR A DISPLAY CARTON OR SIMILAR ARTICLE

Application filed November 19, 1930. Serial No. 37,722. Term of patent 14 years.

To all whom it may concern:

Be it known that EVERETT M. SALISBURY, a citizen of the United States, residing at Providence, in the county of Providence and State of Rhode Island, has invented certain new, original, and ornamental Design for a Display Carton or Similar Article, of which the following is a specification, reference being had to the accompanying drawings, forming a part thereof.

Fig. 1 is a front elevation of a display carton embodying my new design.

Fig. 2 is a side elevation thereof.

In the embodiment shown the rear of the box is unornamented.

I claim:

The ornamental design for a display carton or similar article substantially as shown and described.

In testimony whereof I affix my signature.

EVERETT M. SALISBURY.
